UNITED STATES PATENT OFFICE.

LEE T. HALLOCK, OF ORANGE VALLEY, NEW JERSEY.

HAT-PACKING RING.

SPECIFICATION forming part of Letters Patent No. 625,727, dated May 23, 1899.

Application filed October 12, 1898. Serial No. 693,356. (No model.)

To all whom it may concern:

Be it known that I, LEE T. HALLOCK, a citizen of the United States, and a resident of Orange Valley, in the county of Essex and 5 State of New Jersey, have invented certain new and useful Improvements in Hat-Pack-
ing Rings, of which the following is a speci-
fication.

This invention relates to new and useful 10 improvements in hat-packing rings, and parti-
cularly to that class known as "scoped" rings, which are particularly adapted for pack-
ing and shipping stiff hats.

It is the object of my invention to produce 15 a scoped hat-packing ring which will readily
conform itself to the varying scopes of hat-
brims and engage the same uniformly
throughout in a manner to positively prevent
any abrasion or marking of the hat by pack-
ing or shipment.

It is further an essential and important ob-
ject of said invention to so construct it as to
permit of the same being manufactured
cheaply from pasteboard by automatic ma-
chinery, thus insuring a practical and desir-
able article.

With the above objects in view my inven-
tion resides and consists in the novel con-
struction shown upon the accompanying
30 drawings, forming a part of this specification,
and upon which similar characters of refer-
ence denote like or corresponding parts
throughout the several figures, and of which—

Figure 1 shows a perspective view of a stiff
35 hat provided, as in shipment, with a ring and
stay of my improved character. Fig. 2 shows,
on a reduced scale, an open view of my im-
proved ring. Fig. 3 is an enlarged vertical
40 cross-section on line 3 3 of Fig. 1. Figs. 4
and 5 show perspective and sectional views
of modified forms of my invention.

Referring to the characters of reference
marked upon the drawings, A represents a
45 hat, B a stay, and C a ring. The rings and
stays in this class of merchandise usually
differ principally in that the stays are deeper
than the rings and in that both edges of the
rings are preferably reinforced, while only
50 the top edges of the stays are so produced.

55 While reinforcement of the edges of a ring
of my present construction is not absolutely
essential, yet I desire to employ a ring of that

character, and as a means of such reinforce-
ment preferably utilize a construction where-
in the edges have been turned or doubled 55
over flat against the body and said doubled
edge turned backward or spread out to give
a broad bearing-surface, which construction
is shown in my former patent, No. 603,444, of
May 3, 1898.

Rings of the above class are usually formed
of special strips of pasteboard by uniting
their free ends with glue, eyelets, or similar
means. I therefore take a strip of paste-
board of the above or like character and by 65
a series of operations thereon alternately
thicken and laterally contract the respective
edges in a manner to transform them from
straight to concave and convex surfaces,
which when the ends of the strips are prop- 70
erly united, as at D in Fig. 1, produce a ring
the sides of which are depressed and the ends
raised, thus forming a ring with the desired
scope.

The means and forms of operations to pro- 75
duce a concave and convex strip may vary,
as will be apparent from the modifications
herein shown; but I prefer to employ the
construction shown in Figs. 1, 2, and 3, where-
in substantially vertical corrugations E are 80
employed to traverse or partially traverse the
face of the ring, as will be apparent, since I
find they are the most practical to produce
and likewise provide a more desirable bear-
ing-surface than can be had in any other 85

manner. These corrugations are preferably
divided into series and are alternately ar-
ranged in the opposite edges of the strip, so
that when the latter is united a series of cor-
rugations appear on the top edge of each side 90
and the end edge of both front and rear of
said ring. Said corrugations may partially
or entirely traverse the face of the strip, but
produce the best results when of a tapering
construction, as shown in Fig. 3—that is to 95
say, one end being very pronounced, while
the opposite end may vanish at the outer
edge or at any intermediate point. It will be
further noted that the corrugations not only
produce a scope as desired, but insure flexi- 100
bility and elasticity to the ring, whereby the
same can be made to snugly engage the hat-
crown, as well as its brim, and also permit
of one-sized ring being employed on several

sizes of hats. The central corrugations of each of the series are preferably the largest and, as shown in Fig. 2, gradually grow smaller on either side and eventually run to nothing, whereupon they again appear upon the opposite edge and grow deeper toward the middle of that series.

I do not limit myself to a ring formed of a number of series of corrugations, since it is perfectly practicable to produce a ring of one continuous series, as shown in the ring C, Fig. 1, and by forming tapering corrugations of varying depths the same object can be accomplished as with a ring made in accordance with the drawing, Fig. 2, or by slightly inclining the corrugations at certain points of the ring it will likewise produce a scope as desired. It will further be obvious that it is not necessary to limit the invention to corrugations of any kind, since the respective edges may be alternately contracted and thickened by other forms of operations—namely, that of rolling, as illustrated in Fig. 4, wherein the alternate edges are flattened and the stock spread or bulged out on the opposite sides. This is thought to be practicable by using thick stock, which is particularly sensitive to this form of operation. My object may also be accomplished by a series of slitting operations, as shown in Fig. 5, wherein the stock may simply be provided with an alternate series of plain or wedge-shaped slits, after which the edges of the ring may be drawn together and bound, as shown, or otherwise finished to provide a smooth bearing-surface.

Having thus described my invention, what I claim, and desire to secure by Letters Patent, is—

1. As a new article of manufacture, a hat-packing ring having alternately thickened

and laterally-contracted upper and lower edges, substantially as described.

2. As a new article of manufacture, a hat-packing ring the opposite edges of which are 45 alternately and laterally contracted by a series of operations, substantially as described.

3. A hat-packing ring or stay formed of pasteboard or like material, and provided with one or more series of tapering vertical 50 corrugations, substantially as and for the purpose set forth.

4. A hat-packing ring or stay formed of pasteboard or similar material and having a series of substantially vertical corrugations, 55 as, and for the purpose specified.

5. A hat-packing ring or stay of the class described, the same comprising one or more series of substantially vertical corrugations, alternately arranged in opposite edges thereof. 60

6. A hat-packing ring of the class specified, the same comprising a series of vertical corrugations adjacent to the top edge of each side of said ring, substantially as described.

7. A hat-packing ring of the class described, 65 the same comprising a series of corrugations in one edge of each side and a similar series on the opposite edge at the front and rear of said ring.

8. As a new article of manufacture a paste- 70 board hat-packing ring having a suitable rib on its upper and lower edges, and one or more corrugations traversing said ring, substantially as described.

Signed at Bridgeport, in the county of Fair- 75 field and State of Connecticut, this 6th day of October, A. D. 1898.

LEE T. HALLOCK.
